LUNCH PAIL

Francis J. Yodesky, 1765 Springdale Road,
Cherry Hill, N.J.

Filed May 20, 1963, Ser. No. 74,947

Term of patent 14 years

(Cl. D58—17)

FIG. 1 is a front perspective view of the lunch pail with the lid partially opened,

FIG. 2 is a rear perspective view thereof with the lid closed,

FIG. 3 is a front elevation view thereof,

FIG. 4 is a right side elevation view thereof,

FIG. 5 is a left side elevation view thereof, and

FIG. 6 is a cross sectional view thereof taken on lines 6—6 of FIG. 3.

The bottom is substantially plane.

I claim:

The new and ornamental design for a lunch pail, substantially as shown and described.
